SHOE

Samuel J. Meyer, Brooklyn, N. Y.

Application July 18, 1934, Serial No. 735,871

2 Claims. (Cl. 36—45)

This invention relates to improvements in shoes and has particular relation to the provision of a reinforcing and supporting member in that portion of the quarter of a shoe which engages the inner side of the foot.

In low shoes particularly women's pumps and oxfords, the opening at the top of the shoe must be sufficiently large to permit the insertion of the foot of the wearer and, consequently, the top 10 of the shoe seldom fits properly the top of the foot of the wearer, the result being that the foot slides back and forth in the shoe causing annoyance to the wearer and irritation and inflammation to the foot. Furthermore, shoes of 15 this type being of light construction easily lose their shape and seldom give the proper support to the feet of the wearer.

It is accordingly an object of the invention to provide a shoe having an improved construction 20 which will lend aid and support to the foot and particularly to the arch of the wearer.

A further object is to provide in a shoe of the above character a device which will strengthen and reinforce the shoe adjacent the quarter and 25 which aids in preserving the shape of the shoe.

Another object is to provide a low shoe such as a pump having no lacing or other fastening means, so constructed that it may be easily applied to the foot of the wearer, but which, nevertheless, when applied will fit snugly, will not 30 slide on the foot, and will lend support to the foot.

In the present invention these results are accomplished by providing a reinforcing or supporting member connected between the shank portion of the sole and the upper part of the quarter on that side of the shoe which engages the inside of the foot.

For a fuller understanding of the invention 40 reference should be had to the accompanying drawing, in which

Figure 1 is a perspective view of a shoe embodying features of the present invention;

Fig. 2 is a cross sectional view in the direction 45 of the arrows on the line 2—2 of Fig. 1;

Fig. 3 is a plan view of a portion of a shoe lining showing one way in which a reinforcing member made in accordance with the present invention may be secured to the quarter of the 50 shoe; and

Fig. 4 is a cross sectional view taken in the direction of the arrows on the line 4—4 of Fig. 3.

In the accompanying drawing a low shoe of 55 the pump style is illustrated, but it is to be

understood that the invention may also be used in other types of shoes.

The pump illustrated is of turned construction although it is to be understood that shoes of other construction may be employed, and comprises generally an upper portion 10, a sole 11, and a heel 12. The upper is composed of suitable material, such as the layer of leather 13, and may be formed in one piece or several pieces secured together in any desired manner. A lining 14 may 10 be secured, as by cement or stitches, to the inside of the upper of the shoe. The lining also may be made of leather, or suitable fabric such as canvas if desired, and may cover the entire inside of the upper portions of the shoe or, as 15 illustrated, may be composed of two sections 15 which extend from the rear of the shoe around the sides and meet at a point in front of the opening on the top of the shoe. The lining on one side of the shoe may be continued completely across the sole of the shoe as shown in Fig. 2.

A suitable counter 16 of conventional construction, formed of relatively stiff material, such as heavy leather, is provided between the lining and the outer surface 13 of the upper and it extends 25 around the back and through the quarters of the shoe. The counter 16 and portion 13 of the upper are secured to the sole of the shoe 17, formed of a piece of heavy leather, by means of stitches 18 extending through the upper, the counter, and a 30 portion of the sole as far as the notches 19 in the manner in which turned shoes are usually formed.

Extending over and suitably secured to the shank portion of the sole is a shank-reinforcing strip 20 shaped so as to provide a suitable shank 35 and preferably formed of heavy leather, and which may have affixed to its lower surface a steel strip (not shown) to serve as a reinforcement. The heel 12 is a conventional wooden heel secured to the sole by cement and nails and having 40 a suitable covering material, preferably similar to that forming the upper, secured around it, and a top lift 21 fastened to the bottom thereof. A portion of the sole adjacent the rear of the shoe is split from the remaining portion of the sole 45 forming a strip or layer 22 which is extended downwardly over and secured to the breast of the heel. A suitable pad or lining 30 may also be placed inside the shoe over the sole.

In the quarter of the shoe on that side which 50 engages the inner side of the foot and extending between the shank portion of the sole and the upper part of the quarter, is a reinforcing and supporting member 23. This member preferably is composed of a strip of relatively stiff leather 55

24, stiffer and heavier than the material from which the lining 14 of the outer surface 13 of the upper portion of the shoe is made and preferably having skived edges. If desired, a facing 5 25, preferably made of the same material as the lining 14, is secured over the outer surface of the strip 24.

The lower edge of the reinforcing member is 10 suitably secured to the shank portion of the sole 17 of the shoe, as by the stitches 18, in the same manner as the counter and upper portion 13 are secured, or if desired it may be cemented thereto. The lower portion of the member 23 is relatively 15 broad and shaped to conform with the shank and extends throughout the shank section from approximately the heel of the shoe to the ball of the foot, and it tapers towards the top, the taper of the upper half preferably being greater than the taper of the lower half as shown. This member is preferably secured adjacent its upper 20 end to a point near the top of the quarter of the shoe and this may be accomplished by forming a slit, as at 26, in the lining 14 and extending the upper edge of the member through the slit and suitably securing it to the lining as by the stitches 25 27. It may, however, be secured directly to the outer layer 13 of the upper or to the face of the lining without passing through the slit 26. The member 23 is shaped and fitted in the shoe so as 30 to conform generally with the shape of the quarter.

The length of the member 23 between the point where it is secured to the shank portion of the sole and the point where it is secured to the upper 35 part of the quarter, is preferably slightly shorter than the length of the lining 14 and the portion 13 forming the quarter between the same points so that the member 23 will be relatively taut and the quarter of the shoe will be relatively loose 40 in relation thereto.

When a shoe embodying such a reinforcing and supporting member is placed on the foot, pressure is exerted on the member 23 by the foot of the wearer in the direction of the arrow 28 in Fig. 2

and the upper part of the quarter will be drawn inwardly by the member 23 in the direction of the arrow 29, thus causing the shoe to fit snugly around the upper portion of the foot. Furthermore, the member 23 will support the foot, particularly the arch, and will strengthen and reinforce the shoe and thereby help preserve its proper shape.

Thus with the construction described and illustrated herein a low shoe is provided which will support the foot of the wearer, which will retain its proper shape even for long periods, and which will properly fit and conform to the foot of the wearer.

I claim:

1. In a low shoe, a reinforcing and supporting member connected between the shank portion of the sole of the shoe and the upper part of the quarter of the shoe on the inside of the shoe and on that side which engages the inner side 20 of the foot, said member being relatively broad at its point of connection with the sole and extending along the shank substantially from the heel to the ball of the foot and tapering towards the top, the degree of said taper increasing progressively to a point adjacent the top of said member and being relatively shorter between the points where it connects to the shoe than the quarter of the shoe between the same two points.

2. In a shoe of the pump style, a reinforcing 30 and supporting member connected between the shank portion of the sole of the shoe and the upper part of the quarter of the shoe on the inside of the shoe and on that side which engages the inner side of the foot, said member 35 being formed of relatively stiff material being relatively broad at its point of connection with the sole and extending along the shank substantially from the heel to the ball of the foot and tapering towards the top and being relatively shorter between the points where it connects to the shoe than the quarter of the shoe between the same two points.

SAMUEL J. MEYER.
